UNITED STATES PATENT OFFICE.

JOHN G. CAPSTAFF, OF ROCHESTER, NEW YORK, ASSIGNOR TO EASTMAN KODAK COMPANY, OF ROCHESTER, NEW YORK, A CORPORATION OF NEW YORK.

DIAPHRAGM CONTROL FOR PROJECTION PRINTERS.

Application filed June 8, 1923. Serial No. 644,277.

This invention relates to photography and more particularly to machines for printing motion picture film by projection. One object of my invention is to provide a machine in which the light is automatically controlled for each scene, so that the machine may run without close attention from an operator after once being started until the reproduction is made from the entire length of master film. Another object is to control the light automatically by means of the lens diaphragm adjustment. Another object is to cause the change to automatically take place through suitable notches on the master film. Another object is to provide a diaphragm which can be readily altered by an automatic mechanism, and other objects will appear hereinafter from the following specification, being illustrated in the accompanying drawings.

In the drawings, wherein like reference characters denote like parts throughout:

Fig. 1 is a side elevation of a machine constructed in accordance with and illustrating one embodiment of my invention;

Fig. 2 is a plan view of a length of master positive film;

Fig. 3 is a similar view of a length of the diaphragm film;

Fig. 4 is a fragmentary detail of a part of the diaphragm control;

Fig. 5 is a fragmentary plan view of a part of the diaphragm film-moving mechanism; and

Fig. 6 is a side elevation of parts of the mechanism shown in Fig. 5.

The present embodiment of my invention consists of a base 1 having a fixed upright portion 2 at one end, and a table 3 at the other end upon which a slidable carriage 4 is mounted on suitable rails 5, upon which it may move. This movement is controlled by a rack 6 with which a worm 7 meshes, there being a hand wheel 8 for turning the worm. With this movement the distance between the gate 9 for the master film M and the gate 10 for the sensitive film F can be altered.

The film band moving mechanism does not form an important part of this invention, being shown merely to illustrate one form of my invention. The film M is carried by a supply reel 12, supported by arm 13 of carriage 4, and is drawn over sprocket 14 against which it is held by guide rollers 15. It

then is looped and passes through guide rollers 16, past gate 9, being drawn down intermittently by the claw 17 after which it passes over guide rolls 18 and to the take-up reel 19 carried by the carriage 4. Reel 12 is held upon a fixed shaft 20 by a latch 21. All the reels are held by similar latches which are of well known construction. Reel 19 is carried by shaft 22 which is rotatably mounted on carriage 4 and is moved by the pulley 23.

Power is applied to the above described parts in the following manner: A motor 24 drives the main shaft 25 through gears 26 and 27. This shaft passes through a bearing 28 through which it may slide as well as turn. A key slot 29 is cut in the shaft and bevel gear 30 is keyed to the shaft so as to turn with it, but the shaft may also slide through this gear. When carriage 4 is moved by wheel 8 the driving relation of shaft 25 and bevel gear 30 remains unaltered.

Bevel gear 30 drives a similar gear 31 which turns a stub shaft 32 carrying a second bevel gear 33 and a pulley 34. Pulley 34 drives pulley 23 by the slip belt 35 to move the take-up reel 19 in the usual manner. Bevel gear 33 drives shaft 36 through bevel gear 37 having affixed thereto bevel gears 38 and 39. Gear 39 through gear 40 drives shaft 41 and wheel 42 which actuates the pulldown claw 17. Bevel gear 38 through a similar gear 43, shaft 44 and gears 45 and 46 drives the sprocket 14. The shutter 47 is also driven by suitable connections to shaft 36. While I have described the driving mechanism somewhat in detail, it is to be understood that this is not a part of my invention, as any suitable film-moving mechanism may be used. I prefer, however, to use gears and shafts rather than sprockets and chains, since this increases the accuracy of the movement of the various parts. It is, of course, necessary to move films M and F in synchronism and as accurately as possible.

Carriage 4 also carries a lamp house 48 on table 49, preferably having adjusting wheels 50 and 51 for the arc carbons, and having a cylinder 52 in which there may be a suitable condenser system.

The fixed side 2 of the machine resembles the side just described excepting that preferably the film F is moved in an opposite di-

100

105

rection. The supply reel 53 is carried by shaft 54 affixed to base 2 and it is latched by the usual member 21. The film F is drawn from this reel by sprocket 55 passing beneath rollers 56, then looped and passing through idlers 57, through gate 10, being intermittently moved by the claw 58, after which it is drawn through idlers 59 to the take-up reel 60 mounted on a shaft 61 driven by pulley 62. Shaft 61 is mounted upon the upwardly extending arm 63.

Power is applied from the main drive shaft 25 as before, through bevel gears 64 and 65. Gear 64, however, is not slidable on shaft 25. Gear 65 drives shaft 66, which, through bevel gear 67 and 68, shaft 69 and gears 70 and 71 moves sprocket 55. Shaft 66 also turns shaft 72 through bevel gears 73 and 74. Shaft 74 carries a pulley 75 driving pulley 62 through a slip belt 76, and likewise drives a wheel 77 which actuates claw 58.

It is common practice to use a master negative film M having a series of scenes which may change very frequently on a single reel. These scenes are of different densities as shown in Fig. 2 at 78 and 79 where a scene changes on the line 80. I preferably notch the film at or near such a density change, as at 81.

In order to provide an automatic machine which will print an entire reel without attention I automatically change the printing light intensity to correspond with the different printing values of the several scenes. This I prefer to do by altering the diaphragm of lens 11 through mechanism controlled by the notch 81 in the film. In this instance a diaphragm band D is punched with a series of openings d^1 , d^2 , d^3 , etc., each opening of which will stop the lens to such an aperture as may be necessary to give the correct exposure to the print from the scene on the negative. Thus for scene I the stop d^1 gives a correctly timed print. For scene II d^2 does the same and so on. The first step, therefore, is to provide a diaphragm strip D, having openings, one for each scene, arranged in the order of the scenes.

I find old film, which has been fogged and developed to a dense black, suitable for this purpose, and I space the openings an equal distance on centers. Each new scene, through notch 81, automatically controls the next diaphragm opening used with the objective as will now be described.

A pair of rails 82 (one behind the other) are supported fixedly at 83 by casting 2, and are slidably supported at 84 by carriage 4. Shoes 85 are slidably wound on the rails and support a housing 86 from which arms 87 and 88 extend. Arm 88 supports a supply reel 89 on a fixed shaft 90 having a latch 21. Arm 87 supports a shaft 91 which may be driven by pulley 92. A take-up reel 93 is held on this shaft by latch 21. The dia-

phragm film D passes from reel 89 to reel 93 over guide roller 94 through the slot or guideway 96 in lens mount 11, between the components of the objective 200 as shown, over sprocket 97, and guide roll 95. Rollers 98 on a shoe 99 hold the film on the sprocket.

It should also be noted that shaft 25 passes directly through housing 86, and slot 100 (Fig. 5) engages a key 101 of bevel gear 102 to drive the following mechanism.

As best shown in Figs. 5 and 6, power is derived from shaft 25 through bevel gear 102 which drives a similar gear 103 pinned to stub shaft 104. This shaft is constantly turned in bearing 105 and it turns clutch block 106 which has a toothed periphery 107. A second shaft 108 is coaxial with 104 and is supported in the end of the clutch block at 108' and in bearing 109. This shaft has pinned to it block 110 and gear 108^a. This gear meshes with a similar gear 108^b of the same size which is carried by a stub shaft 108' which is directly over shaft 108. These gears are necessary in the present instance because here I prefer to move the film D downwardly. If it is to be moved in a reverse direction (as is optional) the segment 111 of the Geneva now shown as mounted on shaft 108 may be mounted directly on shaft 108, and the size of the Geneva parts correspondingly altered. Segment 111 which moves with gear 108^b cooperates with Geneva gear 112 which is affixed to shaft 113, as also is the driving sprocket 97. Lock 110 has a flange 114 against which pawl 115 may ride, and a notch 115' which will act as a stop when engaged by the end 117 of pawl 115. (Fig. 4). Block 110 carries a square pin 116 beveled at 116' and pressed by spring 118 from its seat 119. Obviously when engaged by the beveled end 120 of pawl 115, pin 116 will be held from driving engagement with the toothed periphery 107 of block 106, and, when pawl 115 is raised as in Fig. 4, pin 116 will engage one of the teeth 107 and cause block 110 to be driven therewith.

Pawl 115 is an arm pivoted at 120 to casting 121, and having a tail 122 which may engage an adjustable stop pin 123 in one position, and being normally drawn from that position by a spring 124. The tail 122 is slotted at 125 to receive a pin 126 carried by a yoke 127 on the solenoid core 128. This core may be drawn from dashed line position to that shown in full lines in Fig. 4, by means of the coil 129 when energized. This occurs when battery 130 furnishes power through wires 131 and 132 as switch 133 is closed. Switch bar 133 is pivoted at 134 and carries a bar 135 adapted to contact with spring 136 when roller 137 drops into notch 81 impelled by spring 138 pressing on yoke 139 to which the arm 140 of switch 133

is pivoted. The shaft 141 carrying the yoke and roller is slidably mounted in bearings 142 of plate 143.

As the roller stays in slot 81 a very short time, the circuit is only momentarily made and is then broken. Pawl 115 is drawn by spring 124 against flange 114 and as block 110 turns, beveled end 120' of pawl 115 will engage pin 116 withdrawing it from the toothed periphery 107 after which the end 117 strikes stop 115', thus automatically stopping shaft 108 after a single revolution. The speed of the shaft is such that sprocket 97 moves film D at the same or approximately the same speed as films M and F.

This single turn causes segment 111 to turn a similar distance, in which time roller 145 will engage a slot 146 of Geneva gear 112 turning it, and with it shaft 113 one-quarter of a revolution. Sprocket 97 being pinned to shaft 113, turns a similar distance moving diaphragm film D a space equal to the center to center distance of the apertures d .

The film D is threaded by passing from reel 89 through the slot in lens mount 11, over sprocket 97 and down to reel 93. The idlers 98 can be withdrawn from sprocket 97 by handle 150 which may be drawn out against the spring 151. A door 152 of box 86 may be opened to facilitate threading.

Block 110 carries integral therewith a pulley 160 which transmits motion to pulley 92 of the take-up reel 93 by belt 161 so that motion will only be transmitted when shaft 108 is turned,—that is periodically between scenes. The belt may slip as is usual in take-up reel belts to allow for the changing diameter of the reel.

A rack 170 on the guide rail 82 is provided, and a gear 171 meshes therewith, so that the housing and associated mechanism may be moved by handwheel 172 to focus lens 11. Gear 102 will, of course, slide along shaft 25 when the housing is moved.

To summarize briefly the operation of my machine I will give a typical printing operation when producing positive prints by projection from a master negative. The master negative M is threaded through gate 9 on carriage 4 with the start of scene I at the gate. A sensitive film F is threaded through gate 10 on side 2 of the machine, and a diaphragm band D is threaded through guideway 96 in the objective mount 11 with diaphragm d' between the lens components. By starting motor 24, films M and F run through their gates while film D remains stationary until a notch 81 is reached, corresponding to scene II at gate 9. This causes diaphragm film D to move rapidly to bring diaphragm d^2 into position between the lens components in mount 11. Thus each successive scene automatically positions the proper diaphragm in the lens, thereby

regulating the light automatically so that the required exposure is automatically received by film F.

Obviously numerous changes in construction of the parts necessary to alter the lens diaphragm opening can be made, the drawings showing one convenient form of machine illustrating the principle of my invention. I contemplate as within the scope of my invention all such modifications and equivalents as fall within the following claims.

Having thus described my invention, what I claim as new and desire to secure by Letters Patent is:

1. In a projection printer, two separated gates, mechanism for moving a master strip and a sensitized strip past said gate respectively in timed relation, an optical system for projecting an image from the master strip at one gate upon the sensitized strip at the other gate, adjustable means for controlling the amount of light so projected and positioned between the two films, and means connected to and movable in timed relation with the mechanism and controlling the adjustment of said adjustable means at definite, adjustably predetermined, timed intervals throughout the time when the printer is in operation, whereby the amount of light so projected may be varied at any time in accordance with a predetermined schedule.

2. In a projection printer, two separated gates, mechanism for moving a master strip and a sensitized strip in timed relation past said gates respectively, an objective positioned to project an image from the master strip at one gate upon the sensitized strip at the other gate, a diaphragm with an adjustable aperture at the objective and a mechanism operatively connected to the diaphragm to adjust the aperture thereof and means connected to and movable in timed relation with the first named mechanism and controlling the operation of the second named mechanism at definite, adjustably predetermined, timed intervals throughout the time when the printer is in operation, whereby the aperture of the diaphragm may be adjusted at any time in accordance with a selectively predetermined schedule.

3. In a projection printer, two separated gates, means for moving a master strip and a sensitized strip past said gates respectively, an optical system including a source of light and a condenser for illuminating one gate uniformly and an objective for projecting an image from the master strip at said gate upon the sensitized strip at the other gate, and diaphragm means at the objective controllable by the master strip for controlling the light thus projected.

4. In a projection printer, two separated gates, means for moving a master strip and a sensitized strip past said gates respective-

ly, an optical system comprising an objective for projecting an image from the master strip at one gate upon the sensitized strip at the other gate, diaphragm means at the objective, and means controllable by the master strip for adjusting the effective aperture of said diaphragm means.

5. In a projection printer, two separated gates, means for moving a master strip and 10 a sensitized strip in timed relation past said gates respectively, an optical system comprising an objective for projecting an image from the master strip at one gate upon the sensitized strip at the other gate, adjustable 15 diaphragm means at the objective and means automatically controlled by the master strip for adjusting the effective aperture of said diaphragm means.

6. An apparatus for printing on a strip 20 of sensitized film and comprising two separated gates, a master film comprising a strip with scenes having different printing values and having mechanism controlling means corresponding to said scenes, means for moving said master film and a sensitized film in 25 timed relation past said gates respectively, an objective positioned to project images from said master film at one gate upon the

sensitized strip at the other gate, diaphragm means at said objective, and mechanism controlled by said means on said master film adapted to vary the effective aperture of 30 said diaphragm means.

7. An apparatus for printing on a strip of sensitized material and comprising two 35 separated gates, a master film comprising a strip with scenes having different printing values and having mechanism controlling means corresponding to said scenes, means for moving said master film and a sensitized 40 strip in timed relation past said gates respectively, an objective positioned to project images from said master film at one gate upon the sensitized film at the other gate, a mount for said objective having a guideway, a diaphragm strip having a series of 45 apertures corresponding in size inversely to the printing value of the successive scenes on the master film and mechanism controlled by the means on the master film for advancing said diaphragm strip through said guideway, thereby varying the effective diaphragm aperture of the objective.

Signed at Rochester, New York, this 4th day of June, 1923.

JOHN G. CAPSTAFF.
